Application March 13, 1937, Serial No. 130,647

14 Claims.

(Cl. 95—73)

My invention relates in its broadest aspects to the art of printing and has particular reference to the art of rotary printing. Somewhat more specifically, my invention relates to transfer apparatus for exposing sensitized printing cylinders preparatory to the etching thereof, and especially to transfer apparatus for exposing printing cylinders for use in printing continuous patterns.

The present application is a continuation in part of my co-pending application, Serial No. 702,549 which was filed on December 15, 1933, and which is assigned to the assignee of the present invention. The apparatus described herein differs in certain structural details from the structure of the apparatus disclosed in the above identified application, but the general principles of operation are exactly the same.

The transfer of designs onto printing cylinders by photographic or other methods preparatory to the etching of such cylinders, particularly the transfer of continuous patterns such as are used in wall paper and box covering sheets and the like, has always presented a very serious problem to the art, for the reason that the exact joining up of the pattern during the transfer operation, which is absolutely essential where a continuous pattern is employed, is extremely difficult of attainment. Further, the prior art methods even when possible of accomplishment necessitate the use of carbon tissue or similar procedures which can be carried out only by persons of unusual skill, and even then produce rolls which are often very difficult to duplicate.

Hence, the principal object of the present invention is to provide an improved transfer mechanism whereby pictures, patterns, or designs, especially continuous patterns or designs, may be conveniently transferred by photographic processes from suitable photographic transparencies or the like onto printing cylinders, preferably without requiring the exercise of unusual or exceptional skill by the operator to secure exact matching of the pattern or design and in such manner that convenient and easy duplication of the printing cylinders may be easily accomplished. A further object of the invention is to provide an improved transfer mechanism for photographically transferring a picture, pattern, or design from a photographic plate or transparency to a sensitized printing cylinder by an operation which once initiated becomes entirely automatic and is capable of proceeding to completion with little or no supervision by the operator.

At this point it should be emphasized that while the apparatus of the present invention is particu-

larly suitable for use in transferring continuous designs so as to automatically accomplish exact matching of the design, it is equally suitable for use in the manufacture of rolls which do not require exact matching of the picture or design to be reproduced thereby.

Other objects of the present invention are to provide a transfer mechanism for use in exposing sensitized printing cylinders which shall obviate any need for the use of the carbon tissue or other complicated methods of the prior art; to provide an improved transfer mechanism which shall be extremely flexible in operation so as to permit convenient and easy compensation for the ordinary manufacturing differences and inaccuracies in the dimensions of the roll and the transparency; to provide an improved transfer mechanism which shall be simple and substantially foolproof in operation and which, in addition, shall be capable of producing any number of rolls at any time which are exact duplicates of each other, thereby lending itself particularly to the quantity production of papers printed with all-over designs or patterns or the reprinting of such papers; and, generally, to provide an improved transfer mechanism for use in the manufacture of printing cylinders and the like.

One preferred embodiment of the invention is illustrated in the accompanying drawings. Referring to these drawings,

Figure 1 is an elevational view, partially in section, of a transfer mechanism embodying the features of the present invention;

Figure 2 is a plan sectional view on the general line 2—2 of Figure 1;

Figure 3 is a vertical sectional view on the general line 3—3 of Figure 1;

features of the measuring equipment used in conjunction with the apparatus of the present invention;

Figure 9 is a fragmentary sectional view on the general line 9-9 of Figure 8 more completely illustrating certain of the features of the measuring equipment shown in elevation in Figure 8;

Figure 10 is a plan sectional view on the general line 10-10 of Figure 1 illustrating the mechanism provided for accurately indicating a complete revolution of the printing cylinder; and

Figure 11 is a fragmentary view of a portion of the mechanism utilized for accomplishing matching of the design.

To aid in a complete understanding of the apparatus of the invention, it will, perhaps, be helpful to provide at this point a general summary of the manner of operation and the functions performed by the several structural features thereof. Reduced to its simplest elements, the apparatus includes means for supporting a printing cylinder, which has previously been sensitized, for rotatable movement, a support for the printing plate or photographic transparency having the design or picture thereon which it is desired to transfer to the printing cylinder, and means for moving the photographic transparency longitudinally in tangential contact with the printing cylinder while at the same time directing a relatively narrow, concentrated beam of light through the transparency onto the cylinder along the line of contact therebetween.

The apparatus includes means whereby exact joining of the ends of the design may be accomplished during the exposing operation. This means includes a mechanical arrangement whereby slight slippage may be accomplished along the line of engagement of the printing cylinder and the photographic transparency during the exposing operation, this slippage serving to compensate for whatever slight differences may exist in the length of the design on the transparency and the peripheral length of the printing cylinder.

The word slippage as used therein is intended to include all forms of relative movement whether such movement constitutes slippage, creepage, or a combination of the two.

Other features of the apparatus are a pressure securing means for accomplishing accurate line contact between the printing cylinder and the transparency during the exposing operation, means for preventing excessive heating of the transparency during the exposing operation, means for accurately indicating a complete revolution of the printing cylinder, and means for accomplishing accurate measurement of the peripheral length of the printing cylinder preparatory to the exposing operation and as an aid to the manufacture of the photographic transparency.

Referring particularly to the drawings, it will be seen that the apparatus of the present invention includes a bed plate or main frame 1 preferably of heavy cast construction which is provided with a pair of elongated, cylindrical, pillar uprights 3 supported thereon with their axes in parallel relation. These uprights are connected adjacent the bed plate by a bracing yoke member 5 which also serves to support a pair of drive screws 7 for actuating the mechanism for holding the photographic plate transparency.

Under certain circumstances, as will be pointed out later, it is desirable to operate the drive

screws 7 at relatively high speeds, while during the normal operating conditions it is desirable to operate the screws at low speeds. Accordingly, the apparatus of the present invention is provided with a drive mechanism 9 for the screws 7 which is of a dual speed type. This mechanism includes a suitable electric motor 11 which is connected through speed reducing gearing, indicated generally at 12, and a pair of belts 13 and 14 to a pair of drive pulleys 15 and 16, each journaled for free movement upon the main drive shaft 17 for the lifting screws 7. The motor is of the variable speed, reversing type, and a clutch mechanism 19 operable by a handle 20 is provided intermediate the drive pulleys 15 and 16 for permitting either of those pulleys to be keyed to the main drive shaft 17. The pulley 15 serves as the high speed drive, and the pulley 16 serves as the slow speed drive. It will be understood, of course, that suitable gearing or the like may be substituted for the belts 13 and 14 and their cooperating pulleys 15 and 16.

This main drive shaft 17 for the lifting screws 7 is supported upon the yoke 5 connecting the two uprights 3 by means of suitable bearings 21 and terminates at either end in a small cone pinion 23 each of which pinions is adapted to mesh with a cooperating gear 24 keyed to, and supported upon, the bottom of each of the lifting screws 7. A suitable thrust bearing 25 assures free movement of each of the lifting screws.

The mechanism for supporting the photographic transparency, which will usually constitute a flat glass plate as is illustrated at 26, includes a rigid frame 27 having the general form of a hollow rectangle and preferably made of cast metal such as an aluminum alloy. This frame 27 is adapted to be slidably supported at either end thereof upon the cylindrical uprights 3, the frame including four suitably proportioned collars 29 engaging the uprights 3 with a sliding fit. As will be seen particularly in Figure 3, the rectangularly shaped frame 27 is provided with a removable inner frame 31 adapted to receive the glass plate or other transparency 26 with which the device is used. The inner frame 31 is preferably adjustably supported upon the frame 27 so as to facilitate alignment of the transparency 26. It will be understood, of course, that a film, preferably one backed by a glass plate, may be used instead of the plate transparency 26.

The lower limb of the rectangular main frame 27 is provided with a pair of internally threaded bosses or hubs 33 for engaging the lifting screws 7, and it will be apparent that these screws constitute a convenient means for raising and lowering the frame 27 and the transparency supported thereon at readily controllable speeds. During such movement the uprights serve both as supports and as guides for the frame 27.

The sensitized printing cylinder with which the apparatus is used is adapted to be supported for rotatable movement in tangential contact with the transparency 26, as is illustrated particularly in Figures 2 and 3 of the drawings, the cylinder being identified by the numeral 35. To this end, the apparatus includes a relatively rigid frame 37 provided at its ends with a pair of split clamping members 39 which are adapted to clamp about the uprights 3, as is illustrated particularly in Figures 1, 2, and 4. A bearing 41, preferably of the roller or ball bearing type, is provided at either end of this frame 37 for receiving the shaft 42 upon which the cylinder 35 is supported. The

bearings 41 are slidably supported upon the frame 37 and are provided with a screw adjustment 43 whereby the cylinder 35 may be moved toward, or away from, the transparency so as to make possible the attainment of even line contact between the surface of the cylinder 35 and the surface of the transparency 26 when the apparatus is set up for use.

During operation of the device, it is essential that some means be available for permitting the convenient and accurate determination of a complete revolution of the printing cylinder 35. One such means is illustrated in the drawings, which means, as will be seen by reference particularly to Figures 1, 2, and 10, includes an arm 45 adapted to be clamped upon the end of the supporting shaft 42 for the cylinder and provided at its outer end with an annularly shaped member 47 within which is supported a cross hair 48. The outer end of the arm 45 is adapted to move through a cooperating stationary means 49 supported upon, and in part integral with, one of the clamp supports 39 for the roll supporting frame 31, as is illustrated particularly in Figure 10.

This cooperating means includes an eye piece 51 and a cross hair 52 arranged to cooperate with the cross hair 48 in the end of the arm 45. If desired, an illuminating means may be provided for aiding in determining the coincidence of the cross hairs. The arm 45 is preferably removably mounted as by a screw clamp upon the end of the shaft 42 in order to facilitate handling of the roll and may be of articulated construction to permit adjustment of the cross hair.

As has been suggested previously, to assure accurate transfer of the picture or design upon the transparency 26 to the sensitized surface of the cylinder 35, it is absolutely essential to secure a good line contact between the transparency and the printing cylinder during the exposing operation. This requirement makes it desirable to provide some means for biasing the transparency plate in the direction of the roll. In the apparatus shown in the drawings, this means includes a pair of resiliently mounted, elongated presser members 53 preferably made of hard fiber or similar material which will slide easily upon the back of the glass transparency plate. As illustrated particularly in Figures 3, 4, and 6, these members are generally L-shaped and are arranged in a close relationship. To obtain good contact throughout the area of engagement of the transparency 26 and the cylinder 35, the presser members 53 are supported by a plurality of pivoted arms 54 each of which is individually biased in the direction of the transparency by a suitable spring 55, the tension of which is adjustable by a screw 56. The arms 54 are supported upon and rotate about suitable shafts 57 which in turn are supported upon a frame assemblage comprising a pair of parallel support members 58 rigidly connected at either end by a plate 61, as is indicated in Figure 4. The spring mechanisms for biasing the arms are likewise supported on this frame assemblage, as is shown in the drawings.

While it is imperative to secure good contact between the transparency 26 and the sensitized surface of the roll 35 during the transfer operation and to obtain such contact through the use of resiliently supported pressure securing members engaging the back of the transparency adjacent the area of contact of the cylinder and the transparency, it is undesirable to have pressure

applied to the back of the transparency when the cylinder is not in place on the machine, due to the possibility of breaking the glass transparency. Because of this, I provide a pair of eccentrically mounted shafts 63 arranged to engage the rearwardly extending portions 65 of each of the sets of arms 54 utilized for supporting the pressure members 53. These shafts are illustrated particularly in Figures 3, 4, and 6, and each is provided at its outer end with a square or hexagonally shaped terminal portion 67 adapted to be engaged by an end wrench or handle so that it may be conveniently rotated. The bearing supports for the shafts 63 are sufficiently tight to hold the shafts in any position to which they may be moved. Thus, when it is desired to relieve the pressure on the presser members 53, it is necessary merely to rotate the shafts 63 about half a turn and thereby withdraw the presser members 53 from engagement with the rear surface of the transparency plate 26.

The adjacent edges of the presser member 53 define a relatively narrow slot 66 the width of which determines the width of the beam of light which may be directed through the transparency 26 onto the cylinder. Hence, it is desirable that these members shall be adjustably mounted, so as to permit convenient change in the width of this slot. This may be done by means of screws 167 passing through vertical slots 168 in the presser members 53 and screwed into tapped holes in the arms 54, as shown in Fig. 4. The permissible limits of the width of the slot 66 depends upon the size of the cylinder being exposed and the fineness of definition which is required in the finished printing cylinder. It is, of course, desirable to use as wide a slot as is possible to minimize the time required for exposure. For a six inch diameter cylinder, it is generally possible to use a slot as wide as .080", and for a fourteen inch diameter cylinder the slot may be as wide as .150". If the slot is wider than this there will be a tendency toward dot reduction during the printing of the cylinder.

It is desirable that the frame assemblage utilized for supporting the slot defining presser members 53 shall be adjustably mounted in order to facilitate setting up of the apparatus and in order that the apparatus may be conveniently adjusted when it is installed. Accordingly, the end portions 61 of this frame assemblage are provided with tongue sections 69 adapted to engage suitable grooves formed within the members 70 disposed intermediate the members 61 and the clamp members 39 which engage the uprights 3, this arrangement being shown particularly in Figures 4 and 7. Suitable cap screws 71 and cooperating slots 72 formed in the end members 61 permit convenient vertical adjustment of the position of the frame assemblage. Horizontal adjustment of the frame assemblage is accomplished by use of similar tongue and groove arrangements 73 formed in the clamp members 39 and the intermediate members 70, suitable screw adjusting means 75 being provided for cooperating with the intermediate members 70, as is illustrated in Figures 2, 7, and 9. It will be apparent that this arrangement is extremely flexible and permits easy and convenient adjustment of the frame assemblage for supporting the presser members 53 and the associated mechanism in either the vertical or the horizontal direction.

The light source mechanism 77 is positioned immediately behind the presser members 53, and in one satisfactory embodiment of the invention in-

cludes a water jacketed reflector housing having a box-like rear portion 79 (Figure 3) within which are disposed a plurality of symmetrically located arc lamps 81. For a roll 24" wide, I have used four Macbeth arc lamps and have also utilized two 100 ampere Pease Heli-o-lites, both arrangements with good success. The box-like rear portion 79 of the reflector housing connects with a wedge shaped section 83, as is illustrated particularly in Figures 3 and 4, this wedge shaped section 83 being likewise water jacketed. By virtue of its shape, the reflector housing serves to direct a narrow concentrated beam of light through the slot 66 and the transparency 26 onto the sensitized surface of the cylinder along the area of engagement of the transparency and the cylinder.

It will be noted that the water jacketing about the wedge shaped section 83 of the reflector is carried up to, and almost in contact with, the presser members 53 utilized for accomplishing good contact between the transparency and the roll. This is an important feature of the present invention, for the reason that it minimizes the liberation of heat at the area of engagement of the transparency 26 and the sensitized cylinder 35 being exposed, and prevents any possibility of the transparency plate cracking during operation of the apparatus.

The light source is preferably supported independently of the other mechanism by means such as the standard indicated at 85 in Figure 3, and to prevent undue heating of the room in which the equipment is used, it is desirable that the reflector housing for the arc lamps shall be provided with an insulating outer closure 77 and a chimney 89. If desired, a ventilating fan may be utilized in conjunction with this outer closure and chimney. During operation of the machine, water or other cooling liquid is continuously circulated through the jacket about the wedge shaped section 83 of the reflector housing and through the jacket of the rear portion 79 of the reflector housing.

It is a well known fact that it is very difficult, if not practically impossible, to make a photographic plate or transparency of sufficiently accurate size to assure the matching of the design or pattern formed on such transparency during a direct transfer operation such as is contemplated by the present invention. Generally, it is possible to make such a transparency within limits in the neighborhood of plus or minus .020", and while under certain circumstances greater accuracy may be obtained, the attainment of such greater accuracy requires unusual skill on the part of the operator and an unreasonably large amount of time. An error in the neighborhood .005" or even less in the match-up of a continuous design on a printing cylinder will completely ruin such cylinder for printing continuous patterns, for the reason that the inaccuracy will show up with sufficient clarity to constitute a most objectionable defect or blemish in the printed sheet.

The apparatus of the present invention, however, permits the attainment of substantially perfect match-up by direct transfer within the limits to which the photographic plate may be conveniently made. The means for accomplishing this match-up is illustrated particularly in Figures 1, 2, and 5 and includes a gear 89 having relatively narrow, helically cut teeth keyed to the supporting shaft 42 for the printing cylinder 35. The teeth of this gear 89 are adapted to mesh with an adjustably mounted rack 91 which is likewise provided with helically cut teeth of

the same angle, as is illustrated particularly in Figure 5. In one particularly satisfactory embodiment of the invention, the teeth of the gear 89 and the rack 91 are cut at an angle of 15°. The rack 91 is horizontally adjustably supported upon the main frame 27 of the transparency support by a support means which includes two adjusting screws 92, and is angularly adjustable independently of the support means in a vertical plane about a central pivot axis 91' within definite limits, suitable locking and adjusting screws 93 rigidly supported upon the main supporting frame 27 being provided for accomplishing this angular adjustment. The pitch diameter of the gear 89 is exactly the same as the diameter of the cylinder 35, and it will thus be immediately apparent that relative differences between the peripheral speed of the cylinder 35 and the rectilinear speed of the transparency 26 can be accomplished by angling the rack 91 to either side of the vertical. Clockwise angling of the rack 91, as is indicated by the dotted lines of Figure 11, will cause the peripheral speed of the cylinder 35 to exceed the linear speed of the transparency and vice versa.

This difference in the relative speeds of movement, while very small, results in very slight slippage between the engaging surfaces of the transparency 26 and the roll 35 and makes possible the accomplishment of the exact matching up of the design by compensating for the relative differences in the length of the design on the transparency and the peripheral length of the roll being exposed. This operation will be described more fully in a subsequent paragraph.

While the machine of the present invention is capable of compensating for rather material differences between the length of the design on the transparency 26 and the peripheral length of the cylinder 35 being exposed, the best results are obtained when the length of the design is maintained as nearly equal to the peripheral length of the roll as is possible. Thus, the machine also includes mechanism for accurately determining the peripheral length of the cylinder 35 which is to be exposed thereby. This last mentioned means includes a scale 95 (Figs. 8 and 9) vertically adjustably mounted upon the supporting frame 27 for the transparency 26 and a suitable cooperating eye piece 97 mounted upon one of the clamping members 39 integral with the support for the cylinder.

To measure the peripheral length of a cylinder, that cylinder is placed in position upon its bearing supports 41, the rack 91 is moved to the vertical position, and the gear 89 is meshed therewith. Then the arm 45 with the cross hair 48 is adjusted into coincidence with the stationary cross hair 52 either by adjustment of the articulated connection of the arm 45 or by raising or lowering the frame 27 of the transparency support. With the cross hairs 48 and 52 in exact coincidence, the scale 95 is adjusted to the upper zero point thereof by means of the adjustment screw 99 and the eye piece 97. Then, the machine is operated to raise the transparency supporting frame 27 a sufficient amount to produce exactly one complete rotation of the cylinder 35 which may be very accurately determined by bringing the cross hairs 48 and 52 into coincidence. The exact peripheral length of the cylinder may then be read directly upon the scale 95. It will be understood that the peripheral lengths of even very accurately machined rolls will vary a few thousandths, and that this ar-

5 arrangement or a similar means for accomplishing accurate measurement of that peripheral length is a very important part of the present invention.

Having ascertained the exact peripheral length of the cylinder, a photographic transparency of suitable size is prepared, every effort being made to secure a photographic reproduction of the design, picture, or pattern which is to be transferred to the cylinder having a length 10 exactly equal to the peripheral length of the roll. As mentioned previously, it is substantially impossible to produce a transparency image having a length exactly equal to the peripheral length of the cylinder, and the finished transparency will probably be somewhat in error although the error should not, unless the operator has been unusually careless, be greater than $\pm .020'$.

After the transparency has been prepared, an accurate determination is made of the length of the design or pattern reproduced thereon which is to be transferred to the printing cylinder. The remaining portions of the transparency at either end thereof are then blocked out by any convenient means. Lengths of opaque film stripped onto the transparency are particularly suitable for this purpose. These opaque strips serve to define matching limits of the design or pattern on the transparency which is to be transferred 25 to the printing cylinder, and the longitudinal distance between the two strips will differ from the peripheral length of the roll by the error introduced during the operation of making the transparency.

30 The sensitized roll to which it is desired to transfer the design or pattern is then put in position upon the supporting bearings 41, and these bearings are adjusted by the screws 43 to bring the surface of the roll into tangential contact 35 with the surface of the transparency and at the same time bring the gear 89 into mesh with the rack 91. Any discrepancies in the relative positions of the gear 89 and the rack 91 due to differing thickness of the transparency may be compensated for by the horizontal adjusting screws 92 forming part of the rack support. The eccentric shafts 63 are then turned so as to bring the presser members 53 into engagement with the back of the transparency, thereby assuring good 40 line contact between the surface of the printing cylinder and the film side of the transparency during the exposing operation. It is assumed that the width of the slot 66 and the tension of the biasing springs 55 for the presser members 53 45 have been previously adjusted to the desired value.

The distance separating the two opaque strips which define the upper and lower matching limits of the design on the transparency is measured 50 following the application of the strips to the transparency, and having this value it is a simple matter to adjust the rack 91 angularly in whichever direction is necessary to compensate for the slight differences between the length of the design and the peripheral length of the roll. It is, of course, readily possible to calibrate the rack as an aid to effecting this compensation.

55 In certain instances it may be desirable to make a trial exposure of the portion of the printing cylinder at which the match-up is effected, but ordinarily an experienced operator can accomplish proper adjustment of the rack to assure perfect match-up in the exposed cylinder without requiring experimental or preliminary runs.

75 When the adjustment of the rack 91 has been

completed, the transparency support is returned to its lower position so as to bring the upper opaque strip over the slot 66. The apparatus is then in position for accomplishing the exposing operation. The clutch mechanism is placed in the slow speed position, the light source is energized, and the driving motor started. The exposing operation thereupon proceeds automatically to completion, the transparency being moved longitudinally in tangential contact with the printing cylinder an amount sufficient to bring the lower opaque strip across the slot 66. Operation of the apparatus is then stopped either by manual operation of the motor and light switches, or by an automatic cut off switch. The operating rack 91 and gear 89 assure exact match-up 10 by accomplishing slight uniform slippage between the transparency and the printing cylinder during the exposing operation. The proper speed of movement for accomplishing satisfactory exposure of the sensitized cylinder will, of course, be determined by experiment, and once established for any particular sensitizing material and density of transparency need not be changed.

Following its exposure, the roll is etched in any 15 convenient manner, as by immersion or rotation in a suitable bath of etching acid. Since the process of the present invention does not utilize carbon tissue, it is desirable that the transparency shall have a screen or other means formed 20 therein for defining the support for the doctor blade to be used with the printing cylinder. Of course, a screen for defining supporting lands could be worked in during the exposing operation, but it is simpler to have the screen embodied 25 into the transparency itself. A particularly suitable transparency can be produced by carrying out the methods disclosed in my co-pending application, Serial No. 702,549, transparencies of 30 this type inherently producing proper supporting 35 lands for the doctor blade.

From the foregoing it will be seen that I have disclosed a new and improved transfer mechanism and method of operating the same whereby printing rolls for use in printing continuous patterns or the like may be conveniently and easily manufactured by relatively unskilled operators. The machine in operation is substantially fool-proof; properly adjusted, it automatically compensates for the errors in dimensions which creep 40 into the manufacture of the transparencies; and it makes unnecessary the tedious and unsatisfactory carbon tissue methods of the prior art, while at the same time accomplishing a much more 45 satisfactory match-up.

50 Further, through the use of the machine and method as described in the foregoing, it is possible to produce practically any number of rolls which are substantial duplicates of each other. If the unetched cylinders are machined at all accurately 55 to size they may be produced from the same transparency.

I have also disclosed a number of novel structural arrangements which are of particular importance in carrying out the present invention. 60 In this connection, particular stress should be laid upon the novel arrangement disclosed for accomplishing slight slippage between the roll and the transparency during the printing operation; the novel arrangement of the presser mechanism 65 whereby good line contact is obtained between the transparency and the cylinder at all times during the operation of the device without danger or possibility of breaking the transparency plate; the use of a pair of directly connected lift screws 70

which, in conjunction with the guide means disclosed, accomplishes and assures uniform and positive movement of the transparency support; and the arrangement of the water jacketing means for the lamp housing which, by virtue of the fact that the jacketing is carried up almost in contact with the presser members, very materially minimizes any danger of over heating the transparency during the printing operation.

10 It will be apparent that the principles disclosed in the foregoing may be accomplished by the use of various mechanical arrangements. Accordingly, it is my intention that the accompanying claims shall be accorded the broadest reasonable construction consistent with the state of the art.

15 I claim the following as my invention:

1. In apparatus of the class described, means for supporting a printing cylinder for rotation about its longitudinal axis, a photographic transparency, means including a flat, relatively rigid plate member for supporting said transparency for rectilinear movement while in tangential contact with said cylinder, means for simultaneously rotating said cylinder and moving said transparency in tangential contact therewith, and means, including a gear wheel keyed to said cylinder and an angularly adjustable rack affixed to said transparency support means, which is actuatable during said simultaneous movement of said cylinder and said plate to produce uniform slippage between said transparency and said cylinder along the line of tangential contact therebetween and in a direction substantially perpendicular to such line.

2. In apparatus of the class described, means 35 for supporting a printing cylinder for rotatable movement, means for supporting a photographic plate transparency for rectilinear movement in tangential contact with said cylinder, means for simultaneously rotating said cylinder and for moving said plate in tangential contact therewith, and means including a gear keyed to said cylinder and an adjustable rack rigidly supported upon said support means for said transparency for permitting the accomplishment of relative differences 45 between the peripheral speed of said cylinder and the linear speed of said transparency during the operation of said apparatus.

3. In apparatus of the class described, means for supporting a printing cylinder for rotatable movement, means for supporting a photographic plate transparency for rectilinear movement in tangential contact with said cylinder, means for simultaneously rotating said cylinder and for moving said plate in tangential contact therewith, 50 and means including a gear formed with oblique teeth keyed to said cylinder and an angularly adjustable rack having similar oblique teeth mounted upon said support means for said transparency for permitting the accomplishment of relative differences between the peripheral speed 55 of said cylinder and the linear speed of said transparency during the operation of said apparatus.

4. In apparatus of the class described, a printing cylinder, stationary means for supporting said cylinder for rotative movement, an arm including a cross hair keyed to said cylinder, and cooperating means including a second cross hair supported upon said stationary support means laterally adjacent the path of travel of said first 70 named cross hair whereby accurate determination may be had of a complete revolution of said cylinder.

5. In apparatus of the class described, a printing cylinder, means for supporting said cylinder for rotatable movement about its longitudinal

axis, a photographic transparency, means including a flat, relatively rigid plate member for supporting said transparency for rectilinear movement while in tangential contact with the surface of said cylinder, means for accomplishing simultaneous linear movement of said transparency and rotation of said cylinder in tangential contact therewith, and means for securing intimate engagement between said transparency and said cylinder along the line of tangential contact therebetween, said last mentioned means including a pair of elongated presser members each of which is arranged to bear against the free surface of said transparency support plate at one side of, and adjacent to, said line of tangential contact, 15 a plurality of pivotally supported, spaced arms for supporting each of said presser members at spaced intervals along their length, and spring means for biasing each of said arms in the pressure securing direction.

20 6. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous linear movement of said transparency and rotation of said cylinder in tangential contact 25 therewith, and means for securing intimate engagement between said transparency and said cylinder along the line of tangential contact therebetween, said last mentioned means including a pair of elongated presser members each of which is arranged to bear against the free surface of said transparency support plate at one side of, and adjacent to, said line of tangential contact, 30 a plurality of pivotally supported, spaced arm members for supporting said presser members at spaced intervals along the length thereof, adjustable spring means individually biasing each of said arms in the pressure securing direction, and a single spring release means actuatable to simultaneously remove the biasing force of said 45 spring means upon the arm supports for each of said presser members.

7. In apparatus of the class described, a printing cylinder, means for supporting said cylinder for rotatable movement about its longitudinal axis, a photographic transparency, means including a flat glass plate for supporting said transparency for rectilinear movement while in tangential contact with the surface of said cylinder, means for accomplishing simultaneous linear movement of said transparency and rotation of said cylinder in tangential contact therewith, and means for insuring intimate engagement between said transparency and said cylinder along the line of tangential contact therebetween, said last mentioned means including a pair of elongated presser members each of which is provided with an antifriction bearing strip arranged to bear against the free surface of said transparency support plate at one side of, and adjacent to, said line of tangential contact, a plurality of spaced arms for supporting each of said presser members at spaced intervals along their length, and means for biasing each of said arms in the pressure securing direction.

70 8. In apparatus of the class described, a printing cylinder, means for supporting said cylinder for rotatable movement about its longitudinal axis, a photographic transparency, means including a flat glass plate for supporting said

75

transparency for rectilinear movement while in tangential contact with the surface of said cylinder, means for accomplishing simultaneous linear movement of said transparency and rotation of said cylinder in tangential contact therewith, means for directing a relatively narrow elongated beam of light through said transparency support and the transparency carried thereon onto said cylinder along the line of tangential contact therebetween, and means for securing intimate engagement between said transparency and said cylinder along said line of tangential contact and for controlling the width of the beam of light which is directed through said transparency support plate, said last mentioned means including two elongated presser members each of which is arranged to bear against the free surface of said transparency support plate at one side of, and adjacent to, said line of tangential contact, said presser members extending generally parallel to each other and being spaced apart sufficiently to define a narrow slot-like opening through which said beam of light is directed onto said transparency support plate, a plurality of spaced arms for supporting each of said presser members at spaced intervals along their length, means for biasing each of said arms in the pressure securing direction, and means integral with at least one of said presser members which is adjustable toward and away from the other presser member to vary the width of said slot-like opening therebetween and thereby to vary the width of the beam of light which is directed through said transparency support plate.

9. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous movement of said transparency and rotation of said cylinder in tangential contact therewith, and means for securing intimate engagement between said transparency and said cylinder along the line of tangential contact therebetween, said last mentioned means including a stationary frame, at least one elongated presser member positioned so as to engage the free surface of said transparency support adjacent said line of tangential contact, and at least one spring-pressed support arm mechanically connected at one end to said frame and at the other end to said presser member for supporting said presser member and for biasing that member into engagement with said transparency support plate.

10. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous movement of said transparency and rotation of said cylinder in tangential contact therewith, and means for securing intimate engagement between said transparency and said cylinder along the line of tangential contact therebetween, said last mentioned means including a stationary frame, at least one elongated presser member arranged to bear against the free

surface of said transparency support adjacent said line of tangential contact, and a plurality of spring-pressed support arms mechanically connected at one end to said frame and at the other end to said presser member at spaced intervals along its length for supporting said presser member and for biasing said presser member into engagement with said transparency support plate.

11. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous movement of said transparency and rotation of said cylinder in tangential contact therewith, and means for securing intimate engagement between said transparency and said cylinder along the line of tangential contact therebetween, said last mentioned means including a stationary frame, a pair of elongated presser members each of which is arranged to bear against the free surface of said transparency support plate at one side of and adjacent to said line of tangential contact, and a plurality of spring-pressed support arms each of which is mechanically connected at one end to said frame and at the other end to one of said presser members, said spring-pressed arms serving to support said presser members and to bias those members toward the free surface of said transparency support plate.

12. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous movement of said transparency and rotation of said cylinder in tangential contact therewith, and means for securing intimate engagement between said transparency and said cylinder along the line of tangential contact therebetween, said last mentioned means including a stationary frame, at least one elongated presser member positioned so as to engage the free surface of said transparency support plate adjacent said line of tangential contact, a plurality of spring-pressed support arms mechanically connected at one end to said frame and at the other end to said presser member at spaced intervals along its length for supporting said presser member and for biasing said presser member into engagement with said transparency support plate, and a release means for said presser member actuatable to remove simultaneously the biasing force exerted by said spring-pressed support arms upon said presser member.

13. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for accomplishing simultaneous movement of said transparency and rotation of said cylinder in tangential contact therewith, and means for securing intimate engagement between said transparency and said

- 5 cylinder along the line of tangential contact therebetween, said last mentioned means including a pair of elongated presser members each of which is arranged to bear against the free surface of said transparency support plate at one side of and adjacent to said line of tangential contact, a stationary frame, a plurality of spring-pressed support arms which are mechanically connected at one end to said frame and at the 10 other end to said presser members at spaced intervals along the length thereof, said spring-pressed arms serving to support said presser members and to bias those members toward the free surface of said transparency support plate, and release means for said presser members actuatable to remove the biasing force exerted by said spring-pressed support arms upon each of said presser members.
14. In apparatus of the class described, a printing cylinder, means for supporting said cylinder for rotatable movement about its longitudinal axis, a photographic transparency, means including a flat glass plate for supporting said transparency for rectilinear movement while in tangential contact with the surface of said cylinder, 20 means for accomplishing simultaneous movement of said transparency and rotation of said cylinder in tangential contact therewith, means for direct-
- 25

ing a relatively narrow, elongated beam of light through said transparency support plate and the transparency carried thereon onto said cylinder along the line of tangential contact therebetween, and means for securing intimate engagement between said transparency and said cylinder along said line of tangential contact, said last mentioned means including two elongated presser members each of which is arranged to bear against the free surface of said transparency support plate at one side of and adjacent to said line of tangential contact, said presser members extending generally parallel to each other and being spaced apart sufficiently to define a narrow, slot-like opening through which said beam of light is directed onto said transparency support plate, resilient support means for said presser members actuatable to bias said presser members toward the free surface of said transparency support plate, and an adjustable connection between at least one of said presser members and said support means whereby one of said presser members may be moved relative to the other so as to vary the width of said slot-like opening and thereby the width of the beam of light which impinges upon said transparency support plate.

CHARLES L. HENDERSON.
